UNITED STATES PATENT OFFICE.

WARREN FRASIER, OF PHILADELPHIA, PENNSYLVANIA, ASSIGNOR TO UNITED SHOE MACHINERY COMPANY, OF PATERSON, NEW JERSEY, A CORPORATION OF NEW JERSEY.

WORK-SUPPORT.

1,117,178.

Specification of Letters Patent. Patented Nov. 17, 1914.

Original application filed October 20, 1908, Serial No. 458,630. Renewed July 17, 1912, Serial No. 710,059. Divided and this application filed December 7, 1909. Serial No. 531,798.

To all whom it may concern:

Be it known that I, WARREN FRAZIER, a citizen of the United States, residing at Philadelphia, in the county of Philadelphia and State of Pennsylvania, have invented 5 certain Improvements in Work-Supports, of which the following description, in connection with the accompanying drawings, is a specification, like reference characters on the 10 drawings indicating like parts in the several figures.

This invention relates to jacks such as are employed in shoe machines for supporting boots and shoes, and more particularly to a 15 jack which has provision for adjustment to vary the position of the shoe supported thereon.

An object of the present invention is to 20 provide an improved jack of the above type. To this end the present invention consists in the improved device hereinafter described and claimed.

Referring to the drawings,—Figure 1 is 25 a view in side elevation of a heel breasting machine provided with a jack embodying the present invention; Fig. 2 is a view in rear elevation of a portion of the jack shown in Fig. 1.

In the drawings the present invention is 30 shown embodied in a heel breasting machine of the type set forth in my Patent No. 1,068,423, granted July 29, 1913, of which the present application is a division.

2 denotes the frame of the machine which 35 is provided with a reciprocating breasting knife 4 and a tread plate 6 for limiting movement of the shoe toward the knife. In accordance with the present invention there is provided an improved jack, for sustaining 40 a shoe, which is arranged for adjustment to press the heel of the shoe against a tread plate 6 to properly position the shoe in operative relation to the breasting knife. The jack comprises a post 8, adapted to sustain 45 a shoe support, which is pivoted about a horizontal axis at 10 and arranged for limited swinging movement about said axis, the extent of this movement being determined by the play of a projection 12 in a depression 14. The post 8 carries a vertically adjustable rod 16 provided with arms 18 and 20, carrying respectively a pin 22 to enter the opening in the heel of the last and a toe rest 24 for sustaining the toe of the last.

With this construction it will be seen that the 55 shoe support is adapted to have a swinging movement about the pivot 10 between an outer inclined position in which it may receive a shoe and an inner approximately vertical position in which it may sustain said 60 shoe with its heel properly located in the path of the breasting knife. The rod 16 telescopes within the post 8 and is splined therein as by means of a longitudinal slot 26 in the rod and a plate 28 extending into 65 said slot and secured in the top of said post. A pinion 30 is supported upon the top of the post 8, and has threaded engagement with the rod 16 so that rotation of the pinion will effect longitudinal movement of the rod. 70 Upward movement of the pinion 30 is restrained by means of fingers 32 secured to the post and provided with projections extending into a peripheral groove 34 formed in the hub of the pinion. A segmental rack 75 36 meshes with the pinion and is rigidly secured to a hand lever 38 pivoted on the post at 40, so that by moving said lever the operator may actuate the pinion and raise or lower the shoe support, the arrangement being such that an inward movement of the hand lever causes the shoe support to be raised.

In the use of the jack shown in the drawings, the last which carries the shoe is placed 85 upon the shoe support when the latter is in its outer inclined position. The jack is then swung inwardly about the pivot 10 to position the heel of the shoe in the path of the breasting knife, and the shoe is raised by 90 means of the lever 38 so that the tread of the heel strikes the plate 6 and said heel is firmly clamped between said plate and the last.

It will be seen in the use of the jack de- 95 scribed that although movement may be easily imparted to the shoe support by the hand lever 38 to bring the shoe into operative relation to an operating tool the fact that this movement is transmitted through 100 a pinion which has threaded engagement with the supporting rod of the shoe support obviates any liability of the shoe support yielding to the thrust of the knife in the breasting operation.

Having described my invention, what I 105 claim as new and desire to secure by Letters Patent of the United States is:

1. A shoe support comprising a jack post pivoted at its base for movement into and out of a vertical position, a shoe sustaining rod, said post and rod telescoping one another, adjusting means therefor comprising a pinion threaded on the inner member and having abutting engagement with the outer member, a lever bearing a pivotal relation to said members and extending into position to be conveniently manipulated by the workman using the jack, and a toothed segment supported in operative engagement with said pinion and arranged to be actuated by the lever to turn the pinion and effect relative longitudinal adjustment of the jack post and the shoe sustaining rod.

2. A jack, having in combination, a post pivotally mounted for movement into and out of operative position and provided with a longitudinal recess extending to its upper end, a pinion rotatably mounted in axial alinement with the recess in the post, a rod having threaded engagement with said pinion and arranged for sliding movement in said recess but restrained from rotary movement therein, a hand lever of the second class pivoted upon said post, a gear segment connected with the lever between its pivot and its handle and arranged to mesh with said pinion, and a shoe support carried by said rod.

3. A jack, comprising a post mounted for swinging movement between a position in which it receives a shoe and a position in which the shoe is sustained in working position, a rod mounted for longitudinal adjustment in the post, a hand lever pivoted upon the post arranged to effect the adjustment of the rod by movement in a plane approximately parallel with the plane of movement of the post, and a shoe support carried by said rod.

4. In a machine for operating upon shoes, the combination of a shoe support located beneath the operating devices and mounted for movement into and out of operative position, a hand lever arranged for movement in a vertical plane and extending into proximity to the shoe, and connections between the lever and the support to lift the shoe into operative relation to said devices and rigidly to sustain the shoe, the connection between the lever and the support including means which serves automatically to sustain the support in adjusted position against pressure applied to the work and is responsive to movement of the lever in either direction.

5. In a machine for operating upon the heels of shoes, the combination of a shoe support manually movable to present the shoe under the operating devices, a hand lever arranged for movement in a vertical plane and extending into proximity to the shoe, and a connection between the lever

and the support through which movement of the lever screws the support up or down after the shoe has been positioned.

6. In a machine for operating upon the heels of shoes, the combination of a support manually movable to present the shoe under the operating devices, and a hand lever operatively connected with the support and movable idly therewith in said positioning movement of the support, said lever extending lengthwise of the support into proximity to the shoe and being arranged for movement relatively to the shoe support after the latter has been positioned to raise the shoe into operative relation to said devices.

7. In a machine for operating upon the heels of shoes, the combination of a support manually movable to present the shoe under the operating devices, shoe lifting means, and a hand lever connected with said lifting means and movable idly with the support in said positioning movement, said lever extending into proximity to the shoe and being arranged for further movement to actuate the lifting means after the shoe has been so positioned.

8. A device of the class described, having in combination, a base, a post pivoted thereto, a shoe sustaining rod mounted for movement longitudinally in said post, a lever pivoted to said post on an axis parallel with the pivot of the post, and mechanism between said lever and said rod for moving the rod longitudinally when the lever is moved pivotally relatively to the post.

9. A device of the class described, having in combination, a base, a post movable to and from operative position, a rod mounted for longitudinal movement in said post and adapted to support a shoe, a pinion threaded upon said rod, and toothed means movable in the plane of movement of the post and relatively to the post for effecting rotation of said pinion to move said rod longitudinally.

10. A jack comprising a post mounted for movement between a position in which it receives a shoe and a position in which the shoe is to be operated upon, a shoe lifting rod mounted for longitudinal movement in said post, and a lever arranged to effect movement of the rod by movement of the lever in a plane approximately parallel with the plane of movement of the post.

11. A jack for a breasting machine comprising a member mounted for movement in a plane perpendicular to the breasting knife to bring a shoe horizontally into operative relation thereto, a shoe sustaining rod mounted for longitudinal movement in said member, a hand lever fulcrumed upon said member for movement in the same direction as the member, and mechanism connected with said lever for adjusting said rod ver-

tically and rigidly supporting it when said lever is moved pivotally, whereby the operator, with one hand on the shoe and the other upon the lever, may move both to 5 position the shoe laterally and by operating the lever relatively to the member may move the shoe vertically into position to be operated upon by the knife.

12. In a machine for operating upon the 10 heels of boots and shoes, the combination of a post movable into and out of operative position and provided with a recess, a shoe supporting rod mounted in said recess, a pinion threaded upon said rod, a lever 15 mounted upon the post, and a gear segment carried by the lever and meshing with said pinion, said segment being of large radius in comparison with said pinion whereby the shoe may be quickly raised toward and lowered from the operating devices.

13. In a machine of the class described, the combination of a post, a shoe supporting rod mounted therein, a pinion threaded upon said rod, a hand lever arranged adjacent the shoe support, and connections between said lever and said pinion for rapidly 25

rotating the pinion by comparatively slow movement of the lever through a small arc.

14. In a machine of the class described, the combination of a post mounted for 30 movement horizontally to carry a shoe into and out of position to be operated upon, a shoe supporting rod mounted for vertical movement in the post, a movable member mounted on the post, said rod and member 35 being provided with corresponding inclined engaging surfaces which are longer than the circumference of the rod, and manually operable mechanism adjacent to the shoe support constructed and arranged to move said 40 member to cause rapid relative movement between said inclined surfaces and effect movement of the shoe supporting rod vertically.

In testimony whereof I have signed my 45 name to this specification in the presence of two subscribing witnesses.

WARREN FRASIER.
